UNITED STATES PATENT OFFICE.

FRED W. LORD, OF TIPTON, INDIANA, ASSIGNOR TO THE OAKES MANUFACTURING COMPANY, OF TIPTON, INDIANA, A CORPORATION OF INDIANA.

DRINKING FOUNTAIN FOR POULTRY.

Application filed August 30, 1926. Serial No. 132,581.

My said invention relates to drinking fountains and it is an object of the invention to provide a device of this character for supplying water to poultry and which will automatically maintain a predetermined quantity or weight of water in a receptacle all as will be hereinafter more fully described and claimed.

Referring to the accompanying drawings which are made a part hereof and on which similar reference characters indicate similar parts,

Figure 1 is a side elevation partly in section;

Figure 2, an enlarged fragmentary detail, and

Figure 3, a detail perspective.

In the drawings reference character 10 indicates a base which may be weighted if desired to assist in maintaining the fountain in upright position. Said base is provided with a supply pipe 11, for attachment to a water supply line such as a rigid or flexible pipe, and to said supply pipe 11 is secured an elbow 12 in which is mounted an upright pipe 13. The upper end of the pipe 13 is provided with a reduced opening 14 through which water may flow into a trough or pan 15 formed preferably of a circular shape with an upstanding beaded rim and with an adjoining bottom portion slanting downwardly from said rim and connected with a central inclined portion which slants upwardly to the center of the trough. A sleeve 16 of slightly greater length than the depth of the troughs is secured centrally of the same said sleeve being telescoped over and freely slideable on the pipe 13 and a concave disk 17 is secured about the lower extremity of the sleeve with its periphery secured to the inclined inner portion of the trough. This construction forms a rigid durable support for the trough which will not permit a slight weight on the rim of the same to flex or bend the material to cause it to break away from its support.

The upper end of the sleeve 16 is threaded at 18 and a collar 19 is threaded on said sleeve said collar having a substantially rectangular frame 20 carried thereby, the same being attached to said collar at diametrically opposite points and disposed in the plane of the longitudinal axis of said sleeve. This frame 20 forms means for supporting the trough 15, the upper portion of the frame being adapted to seat on the upper end of the pipe 13 and

in order to deflect the water discharged from the pipe downwardly or to cause the water to spray downwardly into the drinking trough I provide a hollow semi-spherical bell member 21 and mount the same with its center directly above the discharge opening 14 in the pipe 13. Also to provide a positive means for shutting off or preventing the discharge of water from said pipe I utilize a small cup 22 in the central portion of said bell member 21 in cup which is mounted a cushion 23 of rubber or the like material which seats upon the end of the pipe 13. A second deflecting member or semi-circular bell member 24 is threaded on the upper end of the pipe 13 to cause the water to spray outwardly in a sheet away from the said pipe although the same may be omitted if desired.

With the foregoing construction when the pipe 11 is connected with a water supply and the trough or container 15 is elevated water will pass upwardly through the pipe 12 and be deflected downwardly by the bell member 21 and outwardly by the bell member 24 into said trough 15. If the trough were maintained in such position water would overflow but when released the weight of the trough and water therein will press the cushion 23 against the discharge opening 14 in the pipe 13 and function as a valve to cut off the supply of water.

In order to maintain the trough in elevated position to permit water to flow into the same when it is empty or the water therein is below a certain level I provide a collar 25 having a bifurcated extension at one side in which is mounted a lever 27 having a bifurcated forward end 28 with the arms of the same disposed on opposite sides of the pipe 13. A second collar 29 is mounted on said pipe 13 beneath the sleeve 16 of the trough said collar having a pair of depending opposed arms 30 pivoted to the bifurcated end 28 of the lever 27. A slotted weight 31 is mounted on said lever 27 and a set screw 32 is provided for securing the weight on the lever in any desired position of adjustment, so that the same may be varied to vary the quantity of water kept in the trough. The collar 25 is provided with an extension 33 which forms a stop for the arm 27 to limit its downward movement. The weight 31 is fixed in such adjusted position that it will normally hold the arm 27 downward against the projection 33 while at the same time the

forward end of the lever will be lifted and will hold the collar 29 with the trough thereon in elevated position with the cushion 23 out of engagement with the end of the pipe 13 and permit water to flow into the trough but when the water flows into the trough sufficient to overcome the weight and depress the same the cushion 23 will shut-off the supply.

10 I preferably provide a substantially conical shield 34 comprising a ring 35 of a size to fit snugly within the upright rim of the trough 15 and having a plurality of wires extending upwardly and secured between a 15 cap 36 and a conical member 37 by means of a set screw 38, the conical member being preferably provided with grooves in which the wires rest. The wires are preferably spaced apart sufficiently to permit poultry to 20 insert their heads therebetween but they are sufficiently close together to prevent standing in the trough.

It will be obvious to those skilled in the art that various changes may be made in my 25 device without departing from the spirit of the invention and therefore I do not limit myself to what is shown in the drawings and described in the specification but only as indicated in the appended claims.

30 Having thus fully described my said invention, what I claim as new and desire to secure by Letters Patent, is:

1. A drinking fountain comprising an upright supply pipe, a deflecting member mounted adjacent the end of said supply pipe, a second deflecting member mounted in position to seat against the end of said supply pipe, a frame carrying said second deflecting member, and a trough associated with said frame and adapted to move the second deflecting member against the end of the supply pipe for closing the same when

the trough is filled with water, substantially as set forth.

2. A drinking fountain comprising an upright supply pipe, a trough slideable on said supply pipe, said trough having its upper edge terminating below the upper discharge end of the supply pipe, an arm associated with said trough and extending upwardly over the end of the supply pipe for closing the same and shutting off the supply of liquid when the trough is depressed, and a deflector mounted on said supply pipe below its discharge end for preventing the discharge of liquid onto the joint between the supply pipe and the trough mounted thereon, substantially as set forth.

3. A drinking fountain comprising an upright supply pipe, a deflecting member mounted adjacent the end of said supply pipe, means independent of the deflecting member for shutting off the supply of water through the supply pipe, and a trough associated with said means and adapted to move the same for closing the pipe when the trough is filled with water, substantially as set forth.

4. A drinking fountain comprising an upright supply pipe, a trough slideable on said supply pipe, means operated by the trough for shutting off the flow of liquid when the trough is depressed, and a deflector mounted on said supply pipe below its discharge end for preventing the discharge of liquid onto the joint between the supply pipe and the trough mounted thereon, substantially as set forth.

In witness whereof, I have hereunto set my hand at Tipton, Indiana, this 27th day of August, A. D. nineteen hundred and twenty-six.

FRED W. LORD.
